UNITED STATES PATENT OFFICE.

EUGENE T. TAPLEY, OF SYLACAUGA, ALABAMA.

AUTO-THEFT INDICATOR.

1,326,803.

Specification of Letters Patent. Patented Dec. 30, 1919.

Application filed May 12, 1919. Serial No. 296,417.

To all whom it may concern:

Be it known that I, EUGENE T. TAPLEY, a citizen of the United States, residing at Sylacauga, in the county of Talladega and 5 State of Alabama, have invented certain new and useful Improvements in Auto-Theft Indicators, of which the following is a specification.

This invention relates to automobile theft 10 indicators, and pertains particularly to alarms which utilize both audible and visible signals.

The object of the invention is to provide 15 a device of this class in which the unauthorized use of the automobile is indicated by both a detonating, audible signal and a visible electrical signal.

In carrying out my invention I provide 20 a detonating signal which is discharged upon the actuation of a movable part of the automobile, such as the steering gear, and the discharge of which closes the circuit of the electrical signal.

In the accompanying drawings:

25 Figure 1 is a vertical section of part of an automobile showing my device associated with the steering post.

Fig. 2 is a view on an enlarged scale and in section on line 2—2 of Fig. 1, showing the 30 parts of the device in an operable position.

Fig. 3 is a vertical section on line 3—3 of Fig. 2.

Fig. 4 is a detail view of the tripping mechanism in an inoperable position, showing the latch in operable position by dotted lines.

Fig. 5 is an enlarged detached perspective view of the detonating chamber and contacts for the electrical signal, and

40 Fig. 6 is a perspective view of the hammer.

On some movable part of the vehicle, such as the steering post 1, a collar 2 is adjustably fastened by the set screw 3. The collar 45 has a notch 4 in its periphery and will turn with the steering post. A housing 5 surrounds the mechanism and has a cover 6, which may be a part of the floor of the vehicle if desired. A supporting bar 7 extends from the sides of the housing 5 and carries a bracket 8 upon which the trip lever 9 is pivotally mounted. The trip lever has a hook 10 at one end and a latch 11 pivoted to the other end. The latch has ears 55 12 to which a link 13 is pivoted. The link is pivoted at its other end to the collar 14

slidably mounted on the trip lever 9, and can be held in any desired position by the set screw 15.

The latch fits in the notch 4 of the collar 2, and it will be seen that rotation of this post will cause the trip lever to be moved about its pivot. It will also be apparent that the latch is readily lifted out of the notch 4 and swung about its pivot 60 65 into an inoperable position and held there by means of the set screw 15 in the collar 14.

A supporting bar 16 carries the barrel or chamber 17 which is made to receive a blank cartridge (not shown) of any desired caliber, and has a pivoted cover 18 and a lock 19 for closing its rear end. The muzzle of the barrel is fitted with a movable plug 20, carrying the outwardly extending contact arms 21 connected by suitable wires to a source of current, such as a battery 22. Stationary, inwardly projecting contact arms 23 are mounted on a flange 24 of the supporting bar 16 and are connected by suitable wires to a visible signal, 70 75 such as an electric light bulb 25, which may be located wherever desired and illuminate a warning of any suitable type (not shown).

A hammer 26 is fastened to a spring 27, secured to the bar 16 in any preferred manner, as by a slotted pin 28 and pins 29. The hammer has a hook 30 and a striker pin 31.

In order to insure that the plug will engage the contact arms, I provide a guide 90 95 32 which projects from the flange 24 and passes into a hole 33 in the plug 20. The alarm is set by inserting a cartridge in the chamber 17 and fitting the plug 20 in the muzzle thereof. The hammer 26 is drawn 95 back against the action of the spring 27 and the hook 30 is engaged with the hook 10 on the trip lever 9. The latch 11 is lowered into the notch 4 and the cover 6 is locked by any suitable means. If an attempt is 100 made to remove the car, it will be obvious that the steering post must be rotated which will oscillate the trip lever and disengage the hook 10 from the hook 30, thus releasing the hammer which will discharge the cartridge and the explosion will blow the plug 20 out of the end of the barrel and cause the two sets of contact arms to engage and close the circuit of the electrical signal.

A suitable vent is provided for the 110 exhausting of the burnt gases. It will be apparent that the thief will be alarmed by the

explosion and probably desert the car, and if not the electrical signal will warn spectators that the car has been stolen.

I claim as my invention:—

5 1. A mechanically operated theft signal for automobiles, comprising an explosion chamber, a striker for discharging the explosive, a lever engaging said striker, a latch, means for moving said latch, and 10 means for holding said latch out of engagement with said first-mentioned means.

15 2. A mechanically operated theft signal for automobiles, comprising an explosion chamber, a striker for discharging the explosive, a pivoted lever engaging said striker and holding it in position to discharge said explosive, a latch to operate the lever and disengage the striker, means for actuating said latch, and means for

adjusting the latch to connect it with said first mentioned means or to hold it out of engagement therewith.

3. A theft signal for automobiles, comprising an explosion chamber, a striker for discharging the explosive, a pivoted lever 25 engaging said striker and holding it in position to discharge the explosive, means comprising a collar having a notch in its outer periphery, a latch engaging in the notch on the collar operated by said means 30 to operate the lever and disengage the striker, and secondary means for adjusting the latch to connect it with the notch in said collar or to hold it out of engagement therewith.

In testimony whereof I have hereunto subscribed my name.

E. T. TAPLEY.
